[57] CLAIM

The ornamental design for a combined toy nursery table and rocking cradle, as shown and described.

DESCRIPTION

FIG. 1 is a perspective view of a combined toy nursery table and rocking cradle showing our new design; FIG. 2 is a top plan view thereof on a reduced scale; FIG. 3 is a front elevational view thereof on a reduced scale;

FIG. 4 is a left side elevational view thereof on a reduced scale, the right side being substantially a mirror image;

FIG. 5 is a rear elevational view thereof on a reduced scale;

FIG. 6 is a bottom plan view thereof on a reduced scale; FIG. 7 is another perspective view thereof with the toy rocking cradle shown in an exploded condition.
